CLAIM

I claim the ornamental design for the hookah, as shown and described.

DESCRIPTION

FIG. 1 is a perspective view of the hookah.

FIG. 2 is a front view of the hookah without the mouthpiece and connector elements.

FIG. 3 is a side view thereof.

FIG. 4 is a top plan view thereof; and,

FIG. 5 is a bottom plan view thereof.

The hookah is disclosed separately for convenience of illustration.

The broken lines are shown for illustrative purposes only and form no part of the claimed design.
